TERMINAL BOX AND PLUG.

1,188,568.

Specification of Letters Patent. Patented June 27, 1916.

Application filed October 28, 1911, Serial No. 657,382. Renewed August 28, 1913. Serial No. 787,207.

To all whom it may concern:

Be it known that I, ELDA G. SMITH, of Syracuse, in the county of Onondaga and State of New York, have invented a certain 5 new and useful Terminal Box and Plug, of which the following is a specification.

This invention has for its object a terminal box and plug particularly adapted for use in connection with railway cars in 10 which the current used by the electrical appliances of the car is supplied by a storage battery or dynamo on the trucks; and it consists in the combinations and constructions hereinafter set forth and claimed.

15 In describing this invention reference is had to the accompanying drawing in which like characters designate corresponding parts in all the views.

Figure 1 is an elevation of my terminal 20 box and plugs, the contiguous wall or floor of the car being also shown. Fig. 2 is an inverted plan of parts seen in Fig. 1, partly broken away. Fig. 3 is a longitudinal sectional view of parts seen in Fig. 1, the operating means and plug being shown in their 25 positions occupied when the plug is partly out of the terminal box.

1 is the terminal box, which is designed to be connected to the under side of the 30 floor 2 of a car.

3 is the plug movable into and out of the box for bringing the terminals carried by such plug into and out of contact with the terminals within the box 1. The opening 35 in the box through which the plug moves is as large as the greater cross-sectional area of the plug so that the plug can be moved entirely out of the box.

The box 1 is here shown as provided with 40 means as an internally threaded nipple 4 at one end for connection with an electric conduit through which the service wires lead from the box, the box being open at its opposite end and also at the side thereof opposite to the side 5 which is contiguous to the floor 2 of the car.

The terminals 6 within the box extend toward or face the open end of the box and are supported by a block 7 extending transversely of the box midway between the ends thereof, and serving as a partition to divide the box into two compartments 8 and 9, one of which as 8 is partly confined by that por-

tion of the box open at two adjoining sides, that is, at one end and its lower side and the other of which as 9 communicates with the nipple 4, the compartment 8 containing the terminals 6. The lower side of the compartment 9 is opened and closed by a suitable cover 10 which is secured in position in any suitable manner as by screws 110.

55 The wires leading from the box are secured within the compartment 9 to the binding devices 11 carried by the partition 7 and connected to the terminals 6, and upon the removal of the cover 10 said wires and binding devices are easily accessible.

60 The plug 3 comprises a box like portion 12 which is open at two adjoining sides, that is, at one end and its upper side and is reversely arranged with respect to the box 1 so that one open side or end thereof is opposed to the open end of the box, and as the plug is moved substantially rectilinearly into the open end of the box 1 the other open sides of the box and plug are closed by the walls 13 of the box portion of the plug and the wall 5 of the terminal box. The terminals 14 on the plug are carried within such box portion on a block 15 of insulation 75 therein normally projecting below the lower side of the box 1 through the opening in the lower side of the compartment 8, and as the plug 3 is moved into and out of the open end of the box 1, the terminals 14 are moved into and out of engagement with the terminals 6.

70 Owing to the construction of the box and plug, it is impossible to reverse the plug and bring terminals of different polarity into contact. The box 1 is provided with suitable guides 16 within the compartment 8 for guiding and supporting the plug.

75 The plug 3 also includes a suitable shield or box 17 for protecting the wires in circuit with the terminals 14, the shield 17 being supported by the closed side 13 of the box portion 12 and extending at a right angle to the direction of movement of the plug into and out of the terminal box 1. As the plug 3 is moved into the terminal box 1, the base 100 of the shield 17 moves along the opening in the open lower side of the compartment 8 of said terminal box.

80 Means is provided for moving the plug into and out of the box and for holding the same in position, said means having 105

detachable interlocking engagement with the plug. As here shown this means consists of a lever 18 pivoted to the box and a link 19 pivoted to the lever and detachably connected to the plug and preferably having interlocking engagement with the plug. As here shown the lever 18 is bifurcated and the opposite arms thereof are movable on opposite sides of the box and are pivoted at 20 to the box, and the link 19 is in the form of a bail embracing the plug 3, the opposite ends of the bail being movable on opposite sides of the box 1 and pivoted at 21, to the arms of the lever 18 and the intermediate portion 22 of the bail extending at substantially right angles to the ends of the bail and crosswise of the plug and into hook-shaped parts 23 projecting from the outer end of the box like portion 12 of the plug 3. Said hook-shaped parts 23 provide a particularly simple construction for forming slots 24 extending in a direction parallel to the direction of movement of the plug 3 and passages 25 extending at an angle to the direction of movement of the plug and opening into the slots, for permitting the bail 19 to be swung on the pivots 21 to carry the cross bar 22 in a direction at an angle to the direction of movement of the plug 3 into the terminal box, and into and out of the passages 25 into and out of interlocking engagement with walls of the slots 24.

When the plug is in the box, said plug and the lever 18 are held from movement by a suitable locking member 26 extending through aligned openings 27 in ears 28 projecting from the lower side of the nipple 4 and an opening in the lever 18, such lever being movable between the ears when the plug is entirely in the box.

In operation, when it is desired to break connection between the storage battery or dynamo carried by the trucks and the service wires of the car, as when it is necessary to remove the trucks from the car to repair the same, the locking member 26 is removed, and the lever 18 is pulled from its position shown in Fig. 1 to and slightly beyond that shown in Fig. 3, thus moving the plug out of the box. The intermediate portion 22 of the bail 19 is then disconnected from the hooks 23 permitting the plug and parts carried thereby to be wholly disconnected from the box 1.

By my terminal box and plug, the electrical connections between the dynamo or the storage battery and the service wires of the car can be broken without the use of tools and without removing any small parts which might be lost, and the connections can be broken and made by the carmen so that it is unnecessary to call an electrician. Further owing to the shape of the plug and the compartment of the box receiving the same, the plug can only be inserted therein in one

position so that terminals of like polarity only, can be brought into contact with each other.

What I claim is:

1. The combination of a terminal box 70 having a terminal located therein, a plug movable into the box from outside of the box and being movable entirely out of the box and having a terminal for engaging the first-mentioned terminal, and means carried by the box for moving the plug into and out of the same from the outside thereof, said means having detachable interlocking engagement with the plug, substantially as and for the purpose described. 80

2. The combination of a terminal box 75 having a terminal located therein, a plug movable into the box from the outside thereof and having a terminal for engaging the first-mentioned terminal, and means for 85 moving the plug into the terminal box from the outside thereof including a lever pivoted to the box, and a link pivoted to the lever and having detachable engagement with the plug, substantially as and for the purpose 90 specified. 95

3. The combination of a terminal box 100 having a terminal located therein, a plug movable into and out of the box and having a terminal for engaging the first-mentioned terminal, and means for moving the plug into and out of the terminal box comprising a bifurcated lever pivoted to the box and having its arms movable on opposite sides of the box, and a link in the form of a bail pivoted at its opposite ends to the arms of the lever and having its intermediate portion embracing the plug, substantially as and for the purpose set forth. 105

4. The combination of a terminal box 110 having a terminal located therein, a plug movable into the box and having a terminal for engaging the first-mentioned terminal, and means for moving the plug into the terminal box comprising a bifurcated lever pivoted to the box and having its arms movable on opposite sides of the box, and a link in the form of a bail pivoted at its opposite ends to the arms of the lever and having its intermediate portion embracing the plug 115 and having detachable interlocking engagement therewith, substantially as and for the purpose described. 120

5. The combination of a terminal box 125 having a terminal located therein, a plug movable into the box and having a terminal for engaging the first-mentioned terminal, the box having an opening in one side thereof through which the plug moves, said opening being as large as the greatest cross sectional area of the body of the plug whereby the plug is movable through the opening, and means carried by the box for moving the plug into the box, substantially as and for the purpose described. 130

6. The combination of a terminal box having a terminal located therein, a plug movable into the box and having a terminal for engaging the first-mentioned terminal, 5 and means for moving the plug into the box comprising a link in the form of a reciprocating bail having its side portions extending on opposite sides of the box and its intermediate portion crosswise of the plug, 10 the plug having a transverse shoulder engaging the bail and receiving the reciprocating motion thereof, substantially as and for the purpose set forth.

7. The combination of a terminal box 15 having a terminal located therein, a plug movable into the box and having a terminal for engaging the first-mentioned terminal, the box having an opening in one side thereof through which the plug moves, said opening being as large as the greatest cross sectional area of the body of the plug whereby the plug is movable through said opening, and means for moving the plug into the box comprising means having detachable interlocking engagement with the plug and movable into and out of engagement with the plug by a movement in a direction at an angle to the direction of movement of the plug into and out of the box, substantially as and for the purpose described.

8. The combination of a terminal box having a terminal located therein, a plug movable into and out of the box and having a terminal for engaging the first-mentioned terminal, the box having an opening in one side thereof through which the plug moves, said opening being as large as the greatest cross sectional area of the body of the plug whereby the plug is movable 35 through the opening, and means for moving the plug into and out of the box comprising a reciprocating link in the form of a bail and having its side portions extending on opposite sides of the plug and its intermediate portion crosswise of the plug and engaging the same, the plug having a shoulder for receiving the reciprocating motion of the link and the bail having pivotal movement at an angle to its reciprocating movement to carry the intermediate portion thereof into and out of engagement with the shoulder, substantially as and for the purpose specified.

9. The combination of a terminal box 55 and a plug, the box being open at two adjoining sides, and the plug having a box-like portion for entering the terminal box, said box-like portion being open at two adjoining sides and arranged complementally to the box whereby the sides of the box-like portion close the open sides of the terminal box and the closed sides of the terminal box cover the open sides of the plug when the plug is moved into the box, and 60 terminals carried by the box and in the box-

like portion of the plug and arranged to engage during the movement of the plug into the box, substantially as and for the purpose set forth.

10. The combination of a terminal box 70 having means for connection with an electrical conduit at one end and having its other end open and also having one of the sides adjoining said other end open, the box also having a transverse partition therein 75 dividing the interior thereof into two compartments, one communicating with said conduit connecting means and the other being partly confined by the portion of the box having the open end and side, a detachable closure for a side of the compartment communicating with the conduit connecting means, terminals carried by the partition and extending into the compartment open at its end and side, and binding devices carried by the partition and connected to the terminals and located in the compartment which communicates with the conduit connecting means, and a plug comprising a box-like portion open at one end and one side, 80 the box-like portion being arranged complementally to the terminal box whereby the sides of the box-like portion close the open end and side of the box and the closed sides of the box cover the open side and end of the box-like portion of the plug when the plug is in the box, and terminals carried by the box-like portion of the plug and arranged to engage the terminals within the box, substantially as and for the purpose described.

11. The combination of a terminal box having a terminal located therein, a plug movable into the box and having a terminal for engaging the first-mentioned terminal, 105 the box having an opening in one side thereof through which the plug moves, said opening being as large as the greatest cross sectional area of the body of the plug whereby the body of the plug can move through said opening, and means for moving the plug into the terminal box including a lever pivoted to the box, and a link having one end pivoted to the lever and its other end detachably engaging with the plug, substantially as and for the purpose specified.

12. The combination of a terminal box having a terminal located therein, a plug movable into the box and having a terminal for engaging the first-mentioned terminal, the box having an opening in one side thereof through which the plug moves, said opening being as large as the greatest cross sectional area of the body of the plug whereby the body of the plug can move through said opening, and means carried by the box for moving the plug into the box, 120 said means comprising a link having opposing side portions on opposite sides of the 125

box, and a portion arranged at substantially a right angle to said side portions and coacting with the plug, and an actuating part associated with the box and connected to 5 the link, substantially as and for the purpose set forth.

13. The combination of a terminal box having a terminal located therein, a plug movable into the box and having a terminal 10 for engaging the first-mentioned terminal, the box having an opening in one side thereof through which the plug moves, said opening being as large as the greatest cross sectional area of the body of the plug 15 whereby the body of the plug can move through said opening, and means carried by the box for moving the plug into the box, said means comprising a link having opposing side portions on opposite sides of 20 the box and the plug, and a portion arranged at substantially a right angle to said side portions and detachably connected to the outer end portion of the plug and an actuating part connected to the link, substantially 25 as and for the purpose described.

14. The combination of a terminal box having a terminal located therein, a plug movable into the box and having a terminal 30 for engaging the first-mentioned terminal, and means for moving the plug into and out of the terminal box comprising a bifurcated lever pivoted to the box and having its arms movable on opposite sides of the box, and a link having opposing side 35 portions on opposite sides of the box connected to the arms of the lever, and a portion arranged at substantially a right angle to said side portions and coacting with the plug, substantially as and for the purpose 40 specified.

15. The combination of a terminal box having means for connection with an electric conduit at one end thereof and having its other end open, the box also having a 45 transverse partition therein dividing the interior of the same into two compartments, one communicating with said conduit connecting means, and the other being partly confined by the portion of the box having 50 the open end, one of the sides between which the partition is located being open so that one edge of the partition is exposed and the compartment communicating with said conduit connecting means is accessible, a detachable closure for said side of the compartment communicating with said conduit connecting means, a terminal carried by 55 the partition and extending into the compartment open at its end, a binding device 60 carried by the partition and connected to

the terminal and located in the compartment in communication with the conduit connecting means, and a plug movable into the open end of the compartment having said open end, the plug having a terminal 65 thereon, the plug being movable through one of the open sides of the box for carrying the terminal thereof into and out of engagement with the first-mentioned terminal, substantially as and for the purpose 70 specified.

16. The combination of a terminal box having angularly disposed open sides, a terminal within the terminal box, and a plug movable substantially rectilinearly 75 through one of the open sides of the terminal box and provided with means projecting beyond the other open side of the terminal box at an angle to the movement of the plug and movable in the opening 80 in said other open side, and a terminal carried by the plug and coacting with the first-mentioned terminal, the box having an opening in one side thereof through which the plug moves, said opening being as large 85 as the greatest cross sectional area of the plug whereby the plug can move through said opening, substantially as and for the purpose described.

17. The combination of a terminal box 90 having angularly disposed open sides, a terminal within the box and a plug movable through one of the open sides of the box and having a terminal carried thereby which moves, during the movement of said plug, 95 into engagement with the first-mentioned terminal, and a wire shield projecting from the plug and being movable into the other side of the box.

18. The combination of a terminal box 100 having a terminal located therein, a plug movable into and out of the terminal box and having a terminal for engaging the first-mentioned terminal, movable means carried by the terminal box and coacting 105 with the plug for moving the plug relatively to the terminal box and for holding the plug from such movement, and means coacting with the terminal box and said movable means for locking said means from 110 movement relatively to the terminal box.

In testimony whereof, I have hereunto signed my name in the presence of two attesting witnesses, at Syracuse, in the county of Onondaga, in the State of New York, 115 this 2nd day of October, 1911.
